UNITED STATES PATENT OFFICE.

JOHN P. BOGERT, OF OKLAHOMA, OKLAHOMA.

MAIL-HANDLING APPARATUS.

1,249,307.

Specification of Letters Patent. Patented Dec. 11, 1917.

Application filed November 17, 1916. Serial No. 131,917.

To all whom it may concern:

Be it known that I, JOHN P. BOGERT, a citizen of the United States, residing at Oklahoma city, in the county of Oklahoma and State of Oklahoma, have invented certain new and useful Improvements in Mail-Handling Apparatus, of which the following is a specification.

This invention relates to an improved mail handling apparatus and the principal object of the invention is to provide a mail handling apparatus which will be so constructed that by means of the same, a sack may be delivered to a station device and taken from the same as the train passes the station, the station device and the train device being both so constructed that a sack may be either held for delivery or collected thus making it unnecessary to provide special means for holding the sack to be delivered and other means for collecting the sack to be taken up.

Another object of the invention is to so construct this mail handling apparatus that a sack may be taken from a train or delivered thereto with the train moving either up or down the track.

Another object of the invention is to provide a mail handling apparatus in which the station device and the train device will be very simple in construction but at the same time very efficient in operation.

This invention is illustrated in the accompanying drawings, wherein there is shown in perspective the improved mail handling device.

This mail handling apparatus includes a station device and a train device, each of which is so constructed that it may hold a sack for delivery and take up a sack with the train going either up or down the track, the same means being employed for holding the sack to be delivered when the train is moving in one direction as would be used for taking up the sack to be delivered when the train is moving in the opposite direction. The station device is provided with a standard 10 having arms 11 extending from its upper end and in the present instance connected with the standard by the coupling 12. Of course, if desired, these arms could be cast integral with the standard but in the illustration, the standard and arms will be formed of either pipe sections or metal bars connected by the coupling. Each arm 11 is provided with a side pin

or finger 13 extending from the outer side faces of the arms. Clamps 14 are secured to the fingers 13 and when used for holding a sack to be delivered, will extend upon opposite sides of the eye 15 held in engagement with the head of the sack 16 by the bearing 17. This eye carries a ring 18 which will extend as shown at the left of the figure to support the sack and as the eye 15 is positioned between the clamp 14 and the end of the finger 13, the sack will be held against movement and the ring also held in the proper position. This ring terminates in a tongue or extension 19 having side faces 70 provided with the grooves 20, the purpose of which will be hereinafter brought out.

The train device includes a carrying bar 21 which passes through a bearing 22 secured to the door-frame 23 and provided with a set screw 24 so that this carrying bar may be releasably held in an adjusted position. A mail car is provided with a side door at each side and it is to be understood that one of these bearings 22 may be secured 80 to each door-frame thus permitting the train device to be extended from either side of the train desired. It will be also obvious that if desired, a separate train device could be provided for each side of the car. The carrying bar 21 is provided at its outer end with side arms 25, each of which terminates in a head 26 and is provided with an up-standing stationary jaw 27. A movable jaw or finger 28 is pivotally connected with the head 26 and when in the operative position, extends as shown in the drawing. The leaf spring 29 which is secured to the under-face of the side arm, engages the hinge-end of the movable jaw 28 and serves to releasably hold the jaw in the upright position. It will thus be seen that when the sack is suspended from the side arm, the tongue or extension 19 will be positioned between the stationary jaw 27 and the movable jaw 28 100 with these jaws fitting into the side grooves 20 thus preventing the ring 18 from having movement transversely of the side arm.

When in use, the sack to be delivered to the station will be suspended from the train device as shown and the sack to be delivered to the train will be suspended from the station device as shown. The train device will be set to extend the proper distance from the car and as the car moves along the track, it being presumed that the car is moving toward the left in the drawing, the free arm

of the train device will pass through the ring of the sack carried by the station device and the finger 13 of the station device, which is free, will pass through the ring 5 of the sack suspended from the train device. The momentum given the sacks when removed, will cause each sack to move along the arm or finger to its inner end and in the case of the station device, the finger 13 of 10 the arm 11 will pass through the ring and suspend the sack and permit the sack to swing without danger of striking the standard 10. After the sack has been transferred, the station master could remove the 15 sack from the station device and the mail-clerk in the car could release the set screw 24 and draw the carrying bar 21 inwardly thus permitting him to easily remove the 20 sacks therefrom. There has therefore been provided, a mail handling device which is 25 simple in construction but which is very efficient in operation and there has further been provided a mail handling apparatus in which similar structures may be used for suspending a sack to be delivered and for taking up a sack to be collected.

What is claimed is:—

1. In a mail handling apparatus a train device comprising a carrying bar, an arm extending from the carrying bar, a stationary jaw extending above the arm, a movable jaw extending above the arm in operative relation to the stationary jaw and having movement longitudinally of the arm, a sack 30 carrying ring for resting upon the arm be- 35

tween the movable and stationary jaws thereof, and a tongue extending from the ring between the jaws and provided with grooves receiving the jaws and preventing transverse movement of the ring upon the 40 arm.

2. In a mail handling apparatus a train device including an arm, a stationary jaw extending above the arm, a movable jaw pivotally connected with the arm in operative relation to the stationary jaw for movement longitudinally of the arm and yieldably held in a set position, a sack suspending ring for resting upon the arm between the jaws, and a tongue extending from the 45 ring and provided with grooves to receive the jaws and prevent transverse movement of the ring upon the arm.

3. In a mail handling apparatus a train device including an arm, a stationary jaw 50 extending from the arm, a movable jaw pivotally connected with the arm in operative relation to the stationary jaw, the movable jaw having movement longitudinally of the arm and yieldably held in a set position, a 55 sack suspending device for resting upon the arm between the jaws, and a tongue extending from the sack suspending device and extending between the jaws.

In testimony whereof I affix my signature 60 in presence of two witnesses.

JOHN P. BOGERT.
